UNITED STATES PATENT OFFICE.

WALTER S. HALDEMAN, OF CHICAGO, ILLINOIS, ASSIGNOR, BY MESNE ASSIGNMENTS, TO THE BERGER MANUFACTURING COMPANY, OF CANTON, OHIO, A CORPORATION OF OHIO.

CONCRETE-FLOOR CORE.

Application filed February 10, 1922. Serial No. 535,587.

The invention relates to the construction of concrete floors to produce a monolithic formation of the girders, the joists, and the floor slab; and the object of the improvement is to provide a sheet-metal sectional core which can be variously assembled to change the relative proportions and dimensions of the joists and the slab, at any intermediate portion thereof, as may be desired.

10 Floor cores made of sheet metal, sometimes with transverse corrugations, have been formed of a series of transversely arched straight sections of uniform height and width, and tapered terminal sections with the smaller end closed have been used to increase the width of the joists and the depth of the slab at their junction with the girder; but such a formation of cores can only produce joists and a slab of uniform 20 proportion and dimension intermediate the terminal core sections.

The present improvement involves the formation of a core with a plurality of straight sections of differential dimensions 25 as to height or width or both, and an intervening reducing section tapered endwise with respect to height or width or both between adjacent straight sections; so that the relative proportions and dimensions of the 30 joists and slab can be varied at any intermediate place between their junctions with the girder.

By variously assembling differential straight sections and intervening tapered sections, the thickness of the joists and the depth of the slab can be made to place the concrete exactly where it is needed, not only at the ends of the joists or slabs, but anywhere in the middle or intermediate portions thereof, wherever additional thickness or depth is required to take care of concentrated loads or to accommodate plumbing or other pipes or accessories.

An embodiment of the invention is illustrated in the accompanying drawings, forming part hereof, in which;

Figure 1 is an elevation section of a floor across a girder and through the slab between adjacent joists, showing core sections and their temporary supports in position;

Fig. 2, a plan of a floor with the concrete broken away as in Fig. 3 to show the construction at different depths;

Fig. 3, a cross section of joists and slab, as on line III—III, Figs. 1 and 2; 55

Fig. 4, a perspective view of a straight core section;

Fig. 5, a perspective view of a terminal cap;

Fig. 6, a perspective view of a core section 60 tapered in height and width;

Fig. 7, a plan of same;

Fig. 8, a side elevation of same;

Fig. 9, a larger end elevation of same;

Fig. 10, a perspective view of a core section 65 tapered in height only;

Fig. 11, a perspective view of a core section tapered in width only.

Similar numerals refer to similar parts throughout the drawings. 70

The improved core may include a series of straight sections 12, 12' and 12'' with intervening tapered sections 13 and 13', all of which are preferably made of sheet metal with transverse corrugations. 75

As shown, the sides 14, 14' and 14'' of the straight cores, and the sides 15 and 15' of the tapered cores, are preferably inwardly inclined upward from the base flanges 16 of the one and 16' of the other, so as to flare 80 the sides of the joists and permit the cores to be readily removed; and the tops 17, 17' and 17'' of the straight cores, and 18 and 18' of the tapered cores, are preferably crowned slightly in the middle, to increase 85 their arching strength.

Each straight core is uniform in height and width through its length, but at opposite ends of tapered cores the straight cores are of differential heights or widths or both, 90 according to the height or width of the corresponding end of the intervening tapered core; and it will be understood that a series of straight sections, exactly alike as 12 in Fig. 1, are joined together without any intervening tapered section, in those parts of the floor wherein a uniform width for the joists and depth for the slab is desired. 95

The reducing cores may be endwise tapered on each side and also on the top, as shown in Figs. 1 to 3 and 6 to 9, or they may be tapered on the top only as shown in Fig. 10, or on the sides only, as shown in Fig. 11, depending upon the variation desired to be made in the width of a joist or the depth of the slab; and in either event, their ends are 105

joined, as by overlapping one or more corrugations or parts thereof with the corresponding corrugations of the adjoining straight section, as shown in Fig. 1.

6. The base flanges of the cores may be of the same width throughout, but the flanges are preferably increased in width from end to end in the side tapered cores, as shown in Figs. 6 and 11; and extended in width in the 10 narrower straight side cores, as shown in Fig. 2; to make the extreme outside width of the flanges of all the cores will be the same, so that they can all be seated on supporting planks 19, of a uniform width.

15. A closing cap 20 is preferably provided for the end of the terminal section, to form the side of the beam between the ends of the joists, and this cap can be applied to the end of a straight core section 12", as shown in Figs. 1 and 2 or may be applied to the 20 end of a tapered section if it be desired to terminate the end of the core with a reducing section.

25. The several core sections may be made of any convenient length, and two or more tapered or reducing sections or two or more straight sections can be joined directly together, if desired; thus giving great flexibility to the character and shape which can 30 be given to the floor structure.

35. Obviously the slab can be gradually arched from a considerably greater depth at its junction with the girder, to a materially less depth at or near the middle of the span between girders; and likewise, the joists can be gradually reduced from an end width approximately the width of a beam, to a comparatively narrow width, at or near the middle; and in either event the reduced depth 40 or width can be made by a series of steps or tapered sections which can be combined or spaced to suit the exigencies of any particular situation.

I claim:—

45. 1. A core for concrete floor construction or the like, including a straight section having certain cross-sectional dimensions, another straight section having different cross-sectional dimensions, and an intervening tapered section joining the straight sections, the respective ends of the intervening section corresponding in cross-sectional dimensions to the ends of the adjoining straight sections.

50. 2. A core for concrete floor construction or the like, including a straight section having width and height, another straight section having the same width but a different

height, and an intervening tapered section joining the straight sections, the respective ends of the intervening section corresponding in cross-sectional dimensions to the ends of the adjoining straight sections. 60

65. 3. A core for concrete floor construction or the like, including a straight section having width and height, another straight section having the same height but a different width, and an intervening tapered section joining the straight sections, the respective ends of the intervening section corresponding in cross-sectional dimensions to the ends of the adjoining straight sections. 70

75. 4. A core for concrete floor construction or the like, including a straight section having certain cross-sectional dimensions, another straight section having different cross-sectional dimensions, and an intervening tapered section joining the straight sections, all the sections having base flanges extending to a uniform outside width and the respective ends of the intervening section corresponding in cross-section to the ends of the adjoining straight sections. 80

85. 5. A reducing core section for concrete floors and the like, having both ends open and the sides tapered endwise, one of the open ends having certain cross-sectional dimensions for connecting with a straight core section of the same cross-sectional dimensions, and the other open end having different cross-sectional dimensions for connecting 90 with another straight section having the same cross-sectional dimensions.

95. 6. A reducing core section for concrete floors and the like, having both ends open and the top tapered endwise, one of the open ends having certain cross-sectional dimensions for connecting with a straight core section of the same cross-sectional dimensions, and the other open end having different cross-sectional dimensions for connecting 100 with another straight section having the same cross-sectional dimensions.

105. 7. A reducing core section for concrete floors and the like, having both ends open and the sides and top tapered endwise, one of the open ends having certain cross-sectional dimensions for connecting with a straight core section of the same cross-sectional dimensions, and the other open end having different cross-sectional dimensions for connecting 110 with another straight section having the same cross-sectional dimensions.

WALTER S. HALDEMAN.
